Jerome S. Smith, 3750 N. Lake Shore Drive, Chicago, Ill.

Filed Feb. 23, 1961, Ser. No. 64,034

Term of patent 14 years

(Cl. D13—1)

FIG. 1 is a plan view of a panel unit for a room divider or similar article embodying my new design;

FIG. 2 is an end view; and

FIG. 3 is a sectional view taken on the plane of broken line 3—3 in FIG. 1 of the drawings and viewed in the direction indicated.

The sides not shown are substantially the same as the ones shown.

I claim:

The ornamental design for a panel unit for a room divider or similar article, substantially as shown and described.
